(57) **CLAIM**

The ornamental design for a tobacco suction tool, as shown and described.

DESCRIPTION

FIG. 1 is a perspective view from the left side of a tobacco suction tool.

FIG. 2 is a perspective view from the right side thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof.

FIG. 8 is a right side elevation view thereof.

FIG. 9 is an enlarged cross-sectional view taken along the line 9-9 in FIG. 7.

FIG. 10 is a perspective view from the left side showing the state that the battery and the cartridge are separated.

FIG. 11 is a perspective view from the right side showing the state that the battery and the cartridge are separated.

FIG. 12 is an enlarged fragmentary perspective view from the left side showing the state that the battery and the cartridge are separated; and,

FIG. 13 is an enlarged fragmentary perspective view from the right side showing the state that the battery and the cartridge are separated.

The broken lines shown in the drawings illustrate portions of the tobacco suction tool that form no part of claimed design.
